UNITED STATES PATENT OFFICE.

HENRY M. REICHENBACH, OF ROCHESTER, NEW YORK.

ATOMIZING AND NEBULIZING DEVICE.

1,224,020.

Specification of Letters Patent. Patented Apr. 24, 1917.

Application filed March 11, 1913, Serial No. 753,602. Renewed June 28, 1916. Serial No. 106,520.

To all whom it may concern:

Be it known that I, HENRY M. REICHENBACH, a citizen of the United States, residing at Rochester, in the county of Monroe 5 and State of New York, have invented certain new and useful Improvements in Atomizing and Nebulizing Devices; and I do hereby declare the following to be a full, clear, and exact description of the invention, 10 such as will enable others skilled in the art to which it appertains to make and use the same.

My invention relates to improvements in atomizing and nebulizing devices and it 15 consists in the constructions, combinations and arrangements herein described and claimed.

An object of my invention is to provide an improved atomizing and nebulizing device 20 adapted to operate efficiently with either light hydrocarbons or a mixture of light and heavy hydrocarbons.

By subjecting the mixture of light and heavy hydrocarbons to the effect of a blast 25 passing through the conduit in the proper way, I am able to volatilize practically all of the lighter constituents and to reduce to a nebula, that is, a cloud consisting of impalpably fine particles, the heavier constituents 30 of the fuel. The vaporized lighter hydrocarbons and the nebulized heavier portion are carried forward to the engine by a single blast.

A further object of my invention is to 35 provide a simple and compact atomizing and nebulizing device especially adapted for automobile use, which can be readily attached to existing types of engines and adjusted to operate with high efficiency under 40 all service conditions.

In the accompanying drawings forming a part of this application, and in which similar reference symbols indicate corresponding parts in all the views:—

45 Figure 1 is a side elevation, illustrating one embodiment of my invention;

Fig. 2 is a top or plan of the construction shown in Fig. 1;

50 Fig. 3 is a bottom view of the construction shown in Fig. 1;

Fig. 4 is a section on the line 4—4 of Fig. 2;

Fig. 5 is a section on the line 5—5 of Fig. 4;

Fig. 6 is an enlarged fragmentary view 55 of the slotted upper end of one of the fuel feed tubes;

Fig. 7 is a central longitudinal section, 60 similar to Fig. 4, illustrating a modified construction in which the rectangular conduit is provided with a spring deflector plate;

Fig. 8 is a fragmentary plan view, illustrating a modified means for regulating 65 the fuel feed;

Fig. 9 is a section on the line 9—9 of Fig. 8, with parts shown in elevation;

Fig. 10 is an enlarged detail section on the line 10—10 of Fig. 8;

Fig. 11 is a fragmentary plan view, 70 illustrating a further modified construction for regulating the fuel feed;

Fig. 12 is a section on the line 12—12 of Fig. 11; and

Fig. 13 is a section on the line 13—13 of 75 Fig. 11.

Referring to the drawings, 1 indicates an open-ended rectangular conduit substantially uniform in cross section adapted to be secured to the inlet or manifold of an 80 internal combustion engine in any suitable way, as by an elbow 2, or in any desired or convenient manner.

A tank 3 is provided with a feed pipe 4 adapted to seat within a recess in the lower 85 wall of said conduit 1, and carrying a series of closely-spaced tubes 5 extending vertically within said conduit through holes in said lower recess wall thereof; said pipe 4 being shown provided with a series of cleaning apertures axially of the tubes 5 and closed by screw plugs 9, for permitting the ready insertion of a wire, or other implement, for cleaning said tubes. In view of

the fact that a number of such tubes are 95 used, the accidental clogging of one only, is not inhibitory to the working of the engine, which by the help of the air valves will take care of any such temporary failure by drawing more fuel from the others. 100

The tank 3 is firmly secured in position by a strap 6 clamped tightly about the conduit 1 by screws 7 and 8 securing its respective ends to said tank 3 and tube 4. The tank 5 3 is connected to any usual or suitable fuel reservoir by a supply pipe 10 controlled by a valve 11, which is actuated by a float 12 for automatically maintaining the liquid fuel within the tank at a constant predetermined level below the slotted upper portions 10 of the feed tubes 5.

The upper portions of the fuel feed tubes 5 are slotted at 13 and preferably provided with reinforcing bands 14; the upper ends 15 of said tubes being closed by screws 15 adjustably threaded therein for regulating said slots 13. The screws 15 carry cores 16 extending axially within the tubes 5 for forming reduced annular passages for the 20 flow of fuel to said slots 13; thereby insuring sufficient velocity of fuel flow through the tubes 5 to prevent danger of fouling of the interior of the latter when employing heavy fuel oils. The annular passages are of a 25 width slightly less than the width of the slots 13, thereby providing an effective screening action for preventing clogging of said slots by foreign matter contained in the fuel. The perpendicular straight 30 walled, sharp edged narrow slots which I employ, are of very great assistance in effecting proper nebulization of the fluid fuel as it rises in the tubes. The blast, as it passes over the edges of the openings, 35 shaves or planes off the liquid in a continuous very thin film, the parts of which are instantly broken up by the blast, aided by the surface tension of the fluid, into a mist or nebula, formed of intangible minute 40 particles.

If desired, the adjusting screws 15 may be threaded through the upper wall of the conduit 1 and the overlapping portion of the strap 6, and extend closely within the upper 45 ends of said tubes 5; lock nuts 17 being provided for firmly securing said screws in their adjusted positions.

A rectangular plate or valve 18 as wide as the inside of the conduit is attached, as by 50 screws 19, to the bottom wall of the conduit 1, and is inclined upwardly across said rectangular conduit to coöperate with the top wall of the latter to provide a converging nozzle of rectangular cross-section for 55 directing the indrawn air in a strong jet through said conduit across the slotted portions of the closely-spaced tubes 5. The plate or valve 18 is formed of spring metal and adapted to be deflected or actuated by 60 the suction of the engine; the free upper end of said valve being provided with rearwardly-extending fingers 20, preferably curved concentrically to the fixed center of swing of said valve 18; said fingers being

under certain conditions adapted to seat 65 against the top conduit wall and to swing between the several tubes 5 upon opening of said valve by the engine suction, for directing the indrawn jet of air across the slots 13 of the fuel feed tubes 5.

The fingers referred to do not fill the entire space between the tubes, but are so arranged that there is a narrow opening between the side of each finger and the adjacent slot through which opening a narrow 75 stream of air may pass, being deflected past the slot by said fingers.

An adjustable stop 21 is shown threaded through the conduit 1 for limiting, if desired, the swing of said valve 18 to its normal closed position and the resiliency of said valve can be readily adjusted by tightening or loosening its attaching screws 19 to permit slight swing or shifting of said valve on the lower conduit wall. It will be obvious that the valve 18 could be yieldingly maintained seated by a spring in any usual well known manner, if desired. I may, if I desire, attach to the top of the conduit a plate 27 somewhat corresponding to the 80 plate 18 and also directed toward the fuel openings. This plate 27 may also be of spring metal or spring mounting, and normally may rest against the plate 18 when the latter is quiescent or closed. When air 85 begins to pass into the opening, the plate 27 is deflected as well as the plate 18, and the narrow current of air is made to pass between the two plates 27 and 18 and past and between the slots. The set screw 28, in the 90 top of the conduit, is adapted to control the position and flexibility of the plate 27. The deflector plate, being of spring metal, bends or is deflected into a curve, as indicated in 95 Figs. 4 and 7, and thus one wall of the converging nozzle becomes a curved, yielding wall, of which wall the tip is freest and quickest to expand, the air through the opening expanding directly into the conduit where the latter is wide or widest. The 100 expanding feature of the inspired blast, is accentuated or magnified under the conditions; and, as is obvious, this aids in gasifying and 105 nebulizing the fuel.

By the above described construction, the 110 cross-sectional area of the rectangular inlet nozzle will vary directly as the extent of swing of the valve 18 in all various open positions of the latter, thereby insuring a uniform and constant mixture under all 115 service conditions.

By this construction, it will be observed 120 that the air supply above the plate 18 increases as this plate is deflected. Starting from the position just shown in Fig. 4, the 125 deflection of said plate will reach a desirable maximum when the fuel discharge slots occupy about the center line of the above re-

ferred to rectangular inlet nozzle. The air in the center is, of course, swiftest and takes proportionately the largest quantity of fuel. Increase of fuel is thus obtained by directly or indirectly bringing the fuel slots toward the center of the air area at this point.

An auxiliary rectangular valve 22 is pivoted at 23 on the conduit 1 for controlling the admission of an additional air supply through an opening 24 in said conduit and breaking up any eddies that might otherwise form below the plate 18; said valve 22 being actuated by the suction of the engine and yieldingly maintained closed by a light spring 25. The rectangular valve 22 swings to an upwardly inclined position within the conduit, thus directing the air indrawn therepast through said conduit. The currents of air thus directed through the conduit by the valves 22 and 18, together with the fuel atomized by the latter from the slotted fuel-feed tubes 5, impinge upon the inner curved wall of the elbow 2 and are deflected as a uniform and intimately intermixed mixture.

A throttle valve 26 is positioned in the conduit 1 between the fuel-feed tubes 5 and the engine and provided with a crank arm 29 adapted to be manually operated in any well known manner for adjusting said valve.

The above described improved construction and relative arrangement of the fuel-feed tubes 5 and the spring-seated suction valves 18 and 22 and manually-operated valve 26 provides a highly efficient carbureter, adapted to operate advantageously with either light or heavy fuel oils under all service conditions. By the use of an atomizer and nebulizer of the kind described, together with the principal and auxiliary air intake valves, and fuel feed devices of the kind shown, I am enabled to use hydrocarbons of a wide limit of grades. Lighter hydrocarbons, such as naphtha, may be vaporized completely under some conditions, but when the fuel used contains percentages of kerosene or even heavier hydrocarbons, volatilization of these will not occur, particularly at low temperatures. My object is to blow these off in a nebulous, as distinguished from a guttulous condition, surrounded by an atmosphere of completely vaporized lighter hydrocarbon and air, in quantity controlled by the suction of the engine, to meet the needs of the particular fuel, to effect complete combustion.

Figs. 8-10 illustrate a modification in which the slots 13 of the fuel-feed tubes 5 are collectively regulated by a series of screws 30 threaded through the upper wall of the conduit 1, and carrying worm wheels 31 in mesh with a worm 32 provided with a knurled head 33, said worm being journaled in brackets 34 mounted on said screws 30.

This provides a simple self-locking mechanism for accurately and simultaneously adjusting the series of regulating screws 30 and locking the latter in their several adjusted positions.

Figs. 11-13 illustrate a further modification, in which the slots 13 of the fuel-feed tubes 5 are regulated by a series of screws 35 threaded through a cross bar 36 and extending slidably through the conduit 1 into said tubes 5. The bar 36 is provided with trunnions 37 engaging slots 38 in a yoke 39 pivoted in ears 40 on the conduit 1. A rod 41 provided with a knurled head 42 is suitably swiveled in the free end of the pivoted yoke 39, as by a pin 43 on said yoke in engagement with an annular recess in said rod; the lower end of said rod 41 being threaded at 43a in the conduit 1. By this improved construction, the several screws 30 can be readily adjusted independently in the cross bar 36, and the series of screws 35 can be simultaneously adjusted by turning the main adjusting screw rod 41.

I have illustrated and described preferred and satisfactory constructions, but changes could be made within the spirit and scope of my invention.

Cross reference is hereby made to my application Serial No. 771,567, filed July 3, 1913, for carbureters, in which application are, among others, claims directed to the feature of having the feed device so positioned that the draft through the inlet conduit is conducted straight across the feed openings.

I claim:

1. In an atomizer and nebulizer, the combination of an inlet conduit for internal combustion engines, a fuel feed device consisting of a series of tubes opening within said conduit, means for supplying fuel at constant level to said device, and a spring metal valve in said conduit, said valve crossing the conduit from the bottom toward the fuel discharge level, and terminating in fingers swinging to shield or cover openings between tubes of the feed device and to guide air past the tube openings.

2. In an atomizer and nebulizer, the combination of an inlet conduit for internal combustion engines, a fuel feed device consisting of a series of tubes opening within said conduit, means for supplying fuel at constant level to said device, and a spring metal valve in said conduit, said valve crossing the conduit from the bottom toward the fuel discharge level, and terminating in fingers swinging between the tubes of said feed device.

3. In an atomizer and nebulizer, the combination of an inlet conduit, rectangular in cross section, for air for internal combustion engines, a fuel feed device consisting of

a series of tubes opening within said conduit, means for supplying fuel at constant level to said device, and a spring metal valve in said conduit, said valve crossing the conduit from the bottom toward the fuel discharge level, and terminating in fingers swinging between the tubes of said feed device, said fingers being bent at their ends upon a curve concentric with the fixed center of swing.

4. In an atomizer and nebulizer, the combination of an inlet conduit for internal combustion engines, provided with a deflecting plate, a fuel feed device opening within said conduit, said fuel feed consisting of a series of feed tubes provided with slots and means for regulating the size of slots, a spring-seated valve actuated by the engine suction for admitting a jet of air and directing such jet across the fuel feed openings and against said deflecting surface, and a throttle valve in said conduit between said fuel feed device and deflecting surface.

5. In an atomizer and nebulizer, the combination of an inlet conduit for internal combustion engines, a series of feed tubes provided with vertical slots arranged cross-wise within said conduit, means for supplying fuel at a constant level to said tubes, a spring-seated plate or valve actuated by the engine suction for directing air across such slots, and a throttle valve in said conduit between said feed tubes and engine.

6. In an atomizer and nebulizer, the combination of an inlet conduit for internal combustion engines, a series of feed tubes provided with slots within said conduit, adjustable means for regulating such slots, means for supplying fuel at a constant level to said tubes, a spring-seated valve actuated by the engine suction for directing air across such slots, and a throttle valve in said conduit between said feed tubes and engine.

7. In an atomizer and nebulizer, the combination of an inlet conduit for internal combustion engines, a series of feed tubes provided with slots within said conduit, cores extending axially in said tubes to provide reduced annular passages for the flow of fuel to such slots, means for supplying fuel at a constant level to said tubes, a valve actuated by the engine suction for directing air across such slots, and a throttle valve in said conduit between said feed tubes and engine.

8. In an atomizer and nebulizer, the combination of an inlet conduit for internal combustion engines, a series of closely-spaced feed tubes provided with slotted portions within said conduit, means for supplying fuel to said tubes at a constant level below such slots, a spring-seated valve actuated by the engine suction for directing air

between the slotted portions of said closely-spaced tubes, and a throttle valve in said conduit between said tubes and engine.

9. In an atomizer and nebulizer, the combination of a rectangular inlet conduit for internal combustion engines, a closely-spaced series of vertical feed tubes provided with vertically slotted portions opening within said conduit, means for supplying fuel at a constant level to said tubes, and a rectangular member inclined from one wall of said conduit for directing the entering air in a jet across the slotted portions of said tubes.

10. In an atomizer and nebulizer, the combination of a rectangular inlet conduit for internal combustion engines, a closely-spaced series of vertical feed tubes provided with vertically slotted portions opening within said conduit, means for supplying fuel at a constant level to said tubes, and a movable rectangular member inclined from one wall of said conduit and actuated by the engine suction for directing the entering air in a jet across the slotted portions of said tubes.

11. In an atomizer and nebulizer, the combination of a rectangular inlet conduit for internal combustion engines, a closely-spaced series of vertical feed tubes provided with vertically slotted portions opening within said conduit, means for supplying fuel at a constant level to said tubes, a movable rectangular member inclined from one wall of said conduit and actuated by the engine suction for directing the entering air in a jet across the slotted portions of said tubes, and a throttle valve in said conduit between said tubes and engine.

12. In an atomizer and nebulizer, the combination of a rectangular inlet conduit for internal combustion engines, a closely-spaced series of feed tubes provided with slotted portions opening within said conduit, means for supplying fuel at a constant level to said tubes, a rectangular member inclined from one wall of said conduit for directing the entering air in a jet across the slotted portions of said tubes, and fingers on said rectangular member for concentrating such jet of air against the slotted portions of said tubes.

13. In an atomizer and nebulizer, the combination of a rectangular inlet conduit for internal combustion engines, a closely-spaced series of feed tubes provided with slotted portions opening within said conduit, means for supplying fuel at a constant level to said tubes, a movable rectangular member inclined from one wall of said conduit and actuated by the engine suction for directing the entering air in jets across the slotted portions of said tubes, and spring

fingers on said rectangular member for concentrating such jets of air against the slotted portions of said tubes.

14. In an atomizer and nebulizer, the combination of a rectangular inlet conduit for internal combustion engines, a closely-spaced series of feed tubes provided with slotted portions within said conduit, means for supplying fuel at a constant level to said tubes, a spring-seated rectangular valve actuated by the engine suction and inclined from one wall of said rectangular conduit to provide a converging nozzle for the entering air, spring fingers on said valve for concentrating the entering air jets of said nozzle against the slotted portions of said tubes, and a manually-operated throttle valve in said conduit between said tubes and engine.

20 15. In an atomizer and nebulizer, the combination of a rectangular inlet conduit for internal combustion engines, a closely-spaced series of vertical feed tubes provided with vertically slotted portions opening within said conduit, means for supplying fuel at a constant level to said tubes, and rectangular members inclined from opposite walls of said rectangular conduit to provide a converging nozzle for directing the entering air against the slotted portions of said tubes.

16. In an atomizer and nebulizer, the combination of a rectangular inlet conduit for internal combustion engines, a closely-spaced series of feed tubes provided with slotted portions within said conduit, means for supplying fuel at a constant level to said tubes, a spring-seated rectangular valve actuated by the engine suction and inclined from one wall of said rectangular conduit, a rectangular deflector plate inclined from the opposite wall of said conduit for coöperating with said inclined valve to provide a converging nozzle for directing the entering air against the slotted portions of said tubes, adjustable stops for limiting the normally closed positions of said deflector plate and valve, and a throttle valve in said conduit between said tubes and engine.

50 17. In an atomizer and nebulizer, the combination of an inlet conduit for internal combustion engines, a fuel feed device opening within said conduit, means for supplying fuel at a constant level to said device, a valve actuated by the engine suction for directing air through said conduit across the fuel-feed openings, a spring-seated auxiliary valve for directing an additional supply of air through said conduit, and a throttle valve in said conduit between said fuel feed device and engine.

18. In an atomizer and nebulizer, the

combination of an inlet conduit for internal combustion engines provided with a deflecting surface, a fuel feed device opening within said conduit, means for supplying fuel at a constant level to said device, a valve actuated by the engine suction for directing air through said conduit across the fuel feed openings and against said deflecting surface, a spring-seated auxiliary valve for permitting introduction of an additional supply of air through said conduit, and a throttle valve in said conduit between said fuel feed device and engine.

19. In an atomizer and nebulizer, the combination of an inlet conduit, a fuel feed device opening into said conduit, means for supplying fuel at constant level to said device, an inclined plate in said device in the rear of the fuel feed for directing a straight forward blast past said openings, and means whereby an auxiliary blast may be drawn in below said plate.

20. In an atomizer and nebulizer, the combination of an inlet conduit, a fuel feed device, opening into said conduit, means for supplying fuel at constant level, vertical sharp-edged slots, through which said fuel is supplied, an inclined plate in said device in the rear of the fuel feed for directing a straight forward blast past said openings, and means whereby an auxiliary blast may be drawn in below said plate.

21. In an atomizer and nebulizer, the combination of an inlet conduit for internal combustion engines, a fuel feed device consisting of a tube opening within said conduit arranged to discharge directly across the blast through an elongated opening, means for supplying fuel at constant level to said tube, and a spring metal valve in said conduit, said valve crossing the conduit toward the fuel discharge opening, and terminating at or near said opening.

22. In an atomizer and nebulizer, the combination of an inlet conduit for internal combustion engines, a fuel feed device consisting of a slotted tube opening within said conduit arranged to discharge directly across the blast, means for supplying fuel at constant level to said tube at or near the slots, and a yielding deflecting plate in said conduit, crossing said conduit toward, and terminating at or near the fuel discharge opening.

23. In an atomizing and nebulizing device for internal combustion engines, in combination, a conduit for said engine, a slotted tube for supplying fuel through the slots to said conduit arranged to discharge fuel across the blast, and a yielding plate extending across said conduit toward said slots, said plate being adapted to yield to engine suction and form with the opposite wall, a

converging channel, toward the center of which at its inmost part, are the fuel openings.

24. In an atomizing and nebulizing device for internal combustion engines, in combination, a rectangular shaped intake conduit, a fuel device discharging fuel through rectangular sharp edged slots across the blast, and a yielding deflector plate arranged 10 to extend from one side of said conduit toward the other wall near to said slots, said plate adapted to yield to engine suction whereby the opening through which air is admitted increases in area in one direction 15 only, whereby the effective discharge of said slots is increased in correspondence with the deflection of said yielding plate.
25. In a carburetor for internal combustion engines, in combination, an intake conduit, a deflecting plate in said conduit, a fuel feed opening within said conduit in proper relation to said plate, said device consisting of a feed tube, provided with a slot arranged to discharge fuel across the blast and means 25 for regulating the size of the slot, a spring seated valve adapted to be opened by engine suction, arranged in the conduit, for admitting air and directing it across the direction of said slot, and a throttle valve in said conduit between the said tube and the engine.
26. In an atomizing and nebulizing de-

vice, the combination of an inlet conduit for internal combustion engines, a series of feed tubes provided with vertical slots arranged crosswise within said conduit, means for supplying fuel at a constant level to said tubes, cores extending axially within said tubes for forming reduced annular passages, a spring-seated valve or plate actuated by the engine suction for directing air across such slots, 40 and a throttle valve in said conduit between said feed tubes and engine.

27. In an atomizing and nebulizing device for internal combustion engines, in combination, a conduit rectangular in cross section, fuel supplying tubes arranged in said conduit, each of said tubes being slotted and the slots extending in a line crosswise of the conduit, air deflecting means arranged in said conduit so as to divert to and concentrate upon said slots the entering blast of air, said deflecting means being adapted to yield as the air pressure increases, so as to form a converging funnel, the center of which tends to said fuel discharge slots. 55

In testimony whereof, I affix my signature, in presence of two witnesses.

HENRY M. REICHENBACH.
